(57) **CLAIM**

The ornamental design for a scraper bar for a milling machine, as shown and described.

DESCRIPTION

FIG. 1 is a front isometric view of our new scraper bar for a milling machine design;

FIG. 2 is a rear isometric view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
